J. T. Noye,
Flour Packer,

No 15,145,

Patented June 17, 1856.

UNITED STATES PATENT OFFICE.

JOHN T. NOYE, OF BUFFALO, NEW YORK.

CLUTCH FOR FLOUR-PACKERS.

Specification of Letters Patent No. 15,145, dated June 17, 1856.

To all whom it may concern:

Be it known that I, JOHN T. NOYE, of Buffalo, in the county of Erie and State of New York, have invented certain new and 5 useful Improvements in Machines for Packing Flour in Barrels, of which the following description, illustrated by the accompanying drawing, is sufficiently clear and comprehensive to enable others of competent skill to make and use my invention.

10 The nature of my improvement consists in the arrangement herein described for throwing the packer shaft in and out of gear with the driving shaft by means of a 15 triangular self adjusting guard used in connection with a hollow cylindrical chamber and hollow shaft.

Figure 1 is an elevation of a whole packer with parts of the mill to which it is attached. Fig. 2, is a perspective view of the parts upon which my improvement is made showing one of the arrangements for connecting and disconnecting the packer shaft with the hollow or driving shaft W. Fig. 25 3, is an elevation of the parts between the lines x, x, x, x , of Fig. 4, turned around so as to show a side view of the sliding guard e, sometimes used instead of the triangular guard o. Fig. 4, is a vertical section of my improvement cut through the center showing the construction of the chamber and the connection of the two shafts, &c.

30 A, Fig. 1, are parts of the frame of the mill.

B is the barrel in which the flour is packed standing on a movable bed or platform C, which is raised and lowered by the lever D, and rod F, in the usual manner, being fixed in its place at pleasure by 40 the ratchet upon E and a catch E'.

G is a conical part of the flour chest and H, the square portion. The lower or conical portion terminates in a metallic cylinder I, which enters the top of the barrel. Passing through this chest (represented in dotted lines, Fig. 1,) is the packer shaft with the screw packer upon its lower end represented in the same manner. This packer 45 shaft is supported by cross bars within the flour chest H. J, is a coupling in the shaft.

The driving shaft T and cylinder W are hung in bearings m^3 upon the bracket n^3 , which is bolted to the upright post in the 50 frame A; this cylindrical driving shaft is slotted upon each side as represented at s

and these slots terminate at the upper ends in the circular cylindrical chamber K, as shown in section in Fig. 4. A pin f is fixed in the packing shaft, each end of which projects from the shaft and fills the slots above named so that the driving shaft by means of this pin will carry the packing shaft along with it when it revolves, until the packer shaft rises so that the pin may 60 turn in the chamber K.

To prevent the pins from striking the corners formed by the slots and cylindrical chamber (which is found to be a great objection to the use of these packers) either 65 of the methods mentioned below may be used, viz, the triangular self adjusting guard or the sliding guard e. This self adjusting guard seen in Figs. 2 and 3 is hung by a pin in the center and is free to 70 turn in either direction. Its natural position will leave the arms x, x' , inclined to the horizon at about forty-five degrees, one of these arms balancing the other. In its natural position one arm extends across the 75 slot in the driving shaft and as the packing shaft rises the pin passing through one of these slots catches the arm x' and turns it around so that this arm stands nearly vertical, and the upper end of it reaches a little 80 above the base of the hollow cylindrical chamber, so that the pins f are thrown to the upper part of the hollow cylindrical chamber before they can revolve in it. After the pin passes over the top of this 85 arm the arm falls to its natural position by its own weight. After being thrown up to this position the packing shaft is kept here at pleasure by the rod L, and its attachments in the usual manner. The sliding 90 guard e is used sometimes to accomplish the same purpose, being carried up by friction of the pins upon its sides next the slot, and falling by its own weight when the pin passes over it into the cylindrical chamber 95 K. Either of these arrangements accomplish an object in an easy and convenient manner which has heretofore caused much difficulty in the use of these machines. The gear wheels M, and N, are arranged in the 100 105 usual manner as shown in drawings.

The upper end of the packer shaft is attached to the cross lever P, Fig. 1, which has the rod L upon its opposite end. This rod has a rack upon its lower end working 110 upon a cogged wheel upon the same shaft with the hand wheel 2, and also upon the

same shaft with the ratchet wheel R, by which two wheels the packer shaft may be regulated in a manner similar to other machines constructed upon this principle.

5 Having thus described my improvement in the machine for packing flour in barrels what I claim as new and desire to secure by Letters Patent is—

The clutch formed by the hollow shaft w
10 with slots s and chamber K in connection with the round shaft T with driving pins f

and balance or slide guards o to drive the pins up into the chamber in the manner and for the purpose herein set forth.

In testimony whereof, I have hereunto 15 subscribed my name before two subscribing witnesses.

JOHN T. NOYE.

Witnesses:

SIMON SHEARMAN,
WILLIAM F. NOYE.
